HAIR DRIER

Lee S. Watlington, 1204 N. Linden, Bloomington, Ill.

Filed Jan. 23, 1963, Ser. No. 73,288

Term of patent 7 years

(Cl. D86—10)

FIG. 1 is a perspective view of the front and one side wall of the hair drier showing my new design;

FIG. 2 is a perspective view of the rear and one side wall of a hair drier showing my new design; and

FIG. 3 is a side elevational view of a hair drier showing my new design.

The shading on the front and rear face panels indicates contrast.

I claim:

The ornamental design for a hair drier, as shown and described.
